LAST

Filed March 26, 1924

Inventor
GEORGE CLAUSING,

By Paulmunt Paulmunt,

Attorneys

Patented July 13, 1926.

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed March 26, 1924. Serial No. 701,989.

My invention relates to lasts.

It is my object to provide a hinge last in which the link and pins are non-resilient, but in which there is a supplementary resilient element interposed so as to give the requisite resistance to movement of the last parts from collapsed to extended position or vice-versa.

It is a further object of my invention to 10 provide a hinge last in which the connecting and anchoring elements hold the parts to one another and are independent of the element which resists the movement of the parts. It is a further object in such a combination to provide that the anchor centers 15 will be below the pivotal center about which the last parts move when the last parts are expanded and above when they are in collapsed position.

20 Referring to the drawings:

Figure 1 is a section through the last in expanded position.

Figure 2 is a section through the last in collapsed position.

25 Figure 3 is a plan view of the plates and springs connecting the last halves.

Figure 4 is a side elevation of one of the plates.

Referring to the drawings in detail:

30 1 is the heel part of a last and 2 is the toe part. These two parts rock upon one another through a knuckle joint consisting of a semicircular projecting portion 3 and a corresponding concave portion 4. The heel portion of the last is cut away as at 5 to 35 permit of the collapsing of the last. When in expanded position the faces 6 of the last are in engagement with one another to limit the movement of the last parts. The last parts are cut away as at 7 and 8 in the toe 40 and heel parts respectively to permit of the accommodation of the plates and spring. The connecting plates are designated 9 and are provided at either end with elongated 45 eyes 10, through which are passed preferably non-resilient pins 11 which work in the slots 12 in elongated eyes 10.

I prefer to use a pair of these plates 50 spaced from one another and having interposed therebetween a spring with hooked ends 13 and a bent central portion 14. These hooked ends are hooked over the pins 11, so that the tension of the spring serves to hold the parts together and to resist any 55 increase in the length of the line between

the centers of the pins, which occurs when the parts pass over dead center. This center is designated 15. It is obvious that the line joining the centers of the pins 11 passes over this center when the parts are moved 60 from one position to another.

When this movement takes place the pins 11 will move relatively to the connecting links 10.

The pivotal point indicated on the drawings is only approximate, but it is accurate sufficiently to illustrate the principle of construction, as the drawings are not drawn to scale. The fundamental idea is to have the line drawn between the centers of the points 70 of attachment pass over the dead center which in a sense is the equivalent of the pivotal point.

I desire to comprehend within my invention such modifications as may be necessary 75 to adapt it to varying conditions.

Having thus fully described my invention, what I claim as new and desire to secure by Letters Patent, is:

1. In a last, a heel part, a toe part, means 80 to pivot said parts one on the other, means connecting said parts, means to anchor said connecting means in the respective parts, and an independent resilient means connecting said anchoring means and adapted to resist 85 the movement of said parts from one position to another and to hold them in either expanded or collapsed position, said connecting means being adapted to have lateral movement relative to said anchoring means. 90

2. In a last, a heel part, a toe part, means to pivot said parts one on the other, means connecting said parts, means to anchor said connecting means in the respective parts, an independent resilient means connecting said 95 anchoring means and adapted to resist the movement of said parts from one position to another and to hold them in either expanded or collapsed position, said connecting means being adapted to have lateral movement relative to said anchoring means, and said last parts being cut away to receive and enclose said several parts.

3. In a last, a heel part and a toe part 105 arranged to pivot upon one another and to be moved from collapsed to expanded position or vice-versa, non-resilient anchor pins in the respective last parts, a plate connecting said pins and parts and mounted on the pins, and a spring hooked over said pins. 110

adapted to maintain the parts in their respective positions or to resist the movement thereof, said plate having elongated slots in which said pins move to permit the spring 5 to flex when the parts are moved from one position to another.

4. In a last, a heel part, a toe part, means to permit the pivoting of said parts one on the other about a given point, means for connecting said parts to one another adapted to have lateral movement on the points of support of the connecting means on the last parts, means to support the respective ends of the connecting means in the last parts, 10 said connecting means being so arranged that a line drawn between the centers of the points of connection with the last parts will pass over said pivotal point when the parts are moved from one position to another, 15 said line lengthening as the parts move from one point to another and shortening as the parts assume the expanded or collapsed position, and resilient means having either end associated with said points of connection 20 whereby the resilient means will be flexed when the line between said points increases in length. 25
5. In a last, a heel part, a toe part, said parts being adapted to rock one on the other,

anchor pins in the respective parts of the 30 last, links mounted thereon having elongated eyes in the ends thereof, and a spring hooked to each of said pins and located between said links.

6. In a last, a heel part, a toe part, said 35 parts being adapted to rock one on the other, anchor pins in the respective parts of the last, links mounted thereon having elongated eyes in the ends thereof, and a spring hooked to each of said pins and located between said 40 links, said spring having a depression therein midway between its ends.

7. In a last, a heel part and a toe part, such last parts being adapted to move one on the other about a given point, and resilient 45 means connected to each of said parts adapted to hold them together and resist their movement from one position to another, said resilient means consisting of a spring member having a depressed center 50 portion and hooked ends mounted on pins carried by the respective parts of the last, and anchored pins for the ends of the spring member.

In testimony whereof, I affix my signature. 55

GEORGE CLAUSING.
